UNITED STATES PATENT OFFICE.

ARTHUR M. BURNHAM, OF GARDINER, MAINE, ASSIGNOR OF ONE-HALF TO
WILLIAM B. RAND, OF BOSTON, MASSACHUSETTS.

SHUTTER-WORKER.

SPECIFICATION forming part of Letters Patent No. 732,393, dated June 30, 1903.

Application filed May 5, 1902. Serial No. 106,041. (No model.)

To all whom it may concern:

Be it known that I, ARTHUR M. BURNHAM, a resident of Gardiner, in the county of Kennebec and State of Maine, have invented certain new and useful Improvements in Shutter-Workers; and I do hereby declare the following to be a full, clear, and exact description of the invention, such as will enable others skilled in the art to which it appertains to make and use the same.

My invention relates to an improvement in shutter-workers; and it consists in certain novel features of construction and combinations and arrangements of parts, as will be more fully hereinafter described, and pointed out in the claims.

In the accompanying drawings, Figure 1 is a view illustrating my improvements. Fig. 2 is a view in horizontal section. Fig. 3 is a view in section of casing 5. Fig. 4 illustrates the double drum, and Fig. 5 is a modification.

1 represents the outside window-cap, 2 the inside cap, and 3 the window-casing, in which the ordinary sashes are mounted in any well-known manner. To the window-casing hinges 3^a are secured and support an ordinary shutter 4 to be operated by my improvements, as will now be set forth.

5 represents a metal casing, comprising two members tightly secured together by screws, as shown, and one of said members made with a tubular extension 6, having inclined ribs 7 thereon to be driven into an opening in the window-cap and held against withdrawal by a screw 8, passed through a shoulder on the casing 5 and into the window-cap.

In casing 5 a horizontally-disposed worm-wheel 9 is located and made with integral journals 10, supported in bearings in the casing, and one of said journals projecting through the bottom of the casing and made angular, as shown.

A worm 11 is supported in casing 5, meshing with worm-wheel 9, and is provided at one end with a journal 12, revolvably supported in a bearing in the casing, and is made with an angular bore to receive the angular outer end of a shaft 13 and adapted to be turned thereby to transmit motion to the worm-wheel. This shaft 13 is mounted in an elongated tube 14, extending through the window-frame and pro-

jecting some distance into tubular extension 6 to provide a long rigid bearing for the shaft and permit of the adjustment of the tube 14 in extension 6 to exactly fit window-frames of varying thickness by simply moving the tube 14 farther into or drawing it outward from extension 6.

The corner-block 16 or other portion of the window-trim is recessed, as shown, and has mounted therein a double-grooved drum 17, secured on shaft 13 and against the end of tube 14. The intermediate or dividing bead or flange 18 of this drum is notched or recessed, as shown at 19, to permit a single cord 20 to be passed through this notch 19 and be wound in opposite directions around the drum-sections, permitting a single cord to take the place of two, as heretofore required. The ends of this cord 20 are passed over pulleys 22, supported on a short shaft 23, mounted in the outer edge of corner-block 16 and approximately in alinement with the axis of drum 17, and the ends of the cord extend down beside the window-trim to within convenient reach of a person in the room and are provided with suitable rings or handholds 24 to facilitate the operation of the apparatus to turn the shaft 13, worm 11, and worm-wheel 9 in either direction to open or close the shutter, as will now be explained.

On the lower protruding angular end of journal 10 a small bracket 25, having an angular opening to receive the journal, is fitted and is held thereon by a pin 26^a, passed transversely through the journal below the bracket. The outer end of bracket 25 is bifurcated to receive a long arm 26, which is hinged thereto by a pin 27, passed through the bifurcated end of the bracket and arm. The arm is preferably ribbed to strengthen it and has provided on its outer end a downwardly-projecting lug 28 to enter an opening in a short link 29 and be secured against removal by a pin 30, and this link 29 is pivotally connected at its other end to the top of shutter 4 by a pin 31, this connection being preferably strengthened by a metal plate 32, secured to the shutter.

In operation when one end of cord 20 is drawn down to turn drum 17 and shaft 13 the opposite end of the cord will be wound on the

drum. The turning of shaft 13 turns worm 11 and transmits motion to worm-wheel 9 and journal 10, forming an integral portion thereof, and thereby swings arm 26 and, by means 5 of link 29, connecting the outer end of the arm with the shutter, pulls the shutter to the position desired, where it is effectually locked until one end of the cord 20 is again drawn downward.

10. It will be seen that by hinging arm 26 to bracket 25 it enables the arm to be disconnected from the shutter at will by simply removing pin 30, thus permitting the shutter to be taken off its hinges and replaced, as occasion may require. This hinged connection also insures the arms perfect operation regardless of the different arc the shutter may move owing to its becoming sagged or from any other cause it does not move concentric 15 with journal 10.

15. In Fig. 5 I have shown the shaft 13 extending through the trim and having drum 17 secured on its protruding end. A double pulley 33 is secured to the trim by a staple 34 and the 20 cord 20 passed over the pulley, the operation being precisely as above explained.

25. A great many slight changes and alterations might be made in the general form and arrangement of parts described without departing 30 from my invention; and hence I do not limit myself to the precise construction set forth, but consider myself at liberty to make such slight changes and alterations as fairly fall within the spirit and scope of my invention.

35. Having fully described my invention, what I claim as new, and desire to secure by Letters Patent, is—

1. In a shutter-worker, the combination 40 with a two-part casing constructed with an elongated sleeve, a worm-wheel and worm mounted in said casing, the worm being secured to one end of a shaft, a tubular shaft-bearing adjustably secured in said elongated 45 sleeve, a winding-pulley attached to the outer end of the worm-shaft, and means for impart-

ing motion from the worm-wheel to a shutter, substantially as set forth.

2. In a shutter-worker, the combination with a worm-wheel to operate a shutter, of a shaft projecting into the window-casing, a worm on the shaft to engage the worm-wheel, a double drum on the shaft having its intermediate bead or flange notched, and a single cord passed into said notch and wound in opposite directions around the drum. 50

3. In a shutter-worker, a metal casing adapted to have a worm-wheel and worm mounted therein, said casing made in two sections, one section being formed with a shoulder, an elongated sleeve provided with exterior longitudinal ribs, and with a perforated flange, substantially as set forth. 60

4. In a shutter-worker, the combination with a casing provided with an elongated sleeve, a tubular shaft-bearing adjustably endwise in said sleeve, of a worm-shaft mounted in the tubular shaft-bearing and a pulley attached to one end of the shaft, substantially as set forth. 65

5. In a shutter-worker, the combination with a wheel, means for rotating it, and a bracket secured to the axle of the wheel, of an arm hinged at one end to the bracket and connected at its outer end to a shutter, substantially as set forth. 75

6. In a shutter-worker, the combination with a wheel mounted to rotate and means for turning the same, of a bracket connected with said wheel, an arm hinged to said bracket, a lug on the outer end of the arm, a link pivotally connected at one end to a shutter, and having a hole in its opposite end to receive said lug, and a pin to lock the lug in the link. 80

In testimony whereof I have signed this 85 specification in the presence of two subscribing witnesses.

ARTHUR M. BURNHAM.
